UNITED STATES PATENT OFFICE.

MAX BERNSTEIN, OF WASHINGTON, DISTRICT OF COLUMBIA.

SAFETY-POCKET FOR GARMENTS.

SPECIFICATION forming part of Letters Patent No. 644,964, dated March 6, 1900.

Application filed November 20, 1899. Serial No. 737,660. (No model.)

To all whom it may concern:

Be it known that I, MAX BERNSTEIN, a citizen of the United States, residing at Washington, in the District of Columbia, have invented certain new and useful Improvements 5 in Safety-Pockets for Garments; and I do hereby declare the following to be a full, clear, and exact description of the invention, such as will enable others skilled in the art to which 10 it appertains to make and use the same.

The object is to present a safety-pocket combining the greatest simplicity of construction and highest efficiency and durability in use and one that may be added to a garment 15 without increasing its cost or giving a bulky and unfinished appearance to the material of the garment directly covering the pocket, and, furthermore, to effect a saving of material in the construction of said pocket and incidentally in such saving to simplify its construction. 20

The invention consists in the novel construction and combination of parts of a safety-pocket, as will be hereinafter fully described 25 and claimed.

In the accompanying drawings, forming a part of this specification, and in which like letters and numerals of reference indicate corresponding parts, Figure 1 is a view in elevation displaying an ordinary side pocket-blank with the safety-pockets attached thereto. Fig. 2 is a view in vertical section displaying the 30 positions occupied by the pocket proper and the attached safety-pockets. Fig. 3 is a view in elevation displaying an ordinary front pocket-blank with the safety-pockets attached thereto. Fig. 4 is a view, also in elevation, displaying the pocket proper, the inclosed safety-pockets being indicated by dotted lines. 35

Referring to the drawings, A designates an ordinary pocket-blank, and B the safety-pockets. 40

The blank A may be of any suitable material and cut to form either a side pocket for 45 trousers, ladies' dresses, &c., as shown in Fig. 1, or a front pocket for trousers, coats, jackets, &c., as shown in Fig. 3.

As exhibited in Figs. 1 and 2, each pocket proper is provided with two safety-pockets, 50 although it is to be understood that the invention is not to be limited to this number, as a greater number may be employed, if found

desirable or necessary. Where two safety-pockets are employed, one may be used for holding money in the form of coin and the other for holding money in the form of bills. The safety-pockets may be made of the same or of a different material from the pocket proper and may be of other shapes than those shown. 55

One of the principal features of this invention is the saving effected in making the safety-pockets. As heretofore constructed these pockets have been composed of at least two separate pieces of material, one forming the pocket and the other the closing-flap therefor, so that to present two pockets four separate pieces of material have been necessary. Under the mode of construction of the pockets herein shown two pockets are produced from three pieces of material, thereby saving both in goods and in the time necessary to attach the ordinary fourth piece in position. This slight saving in time and material may appear immaterial; but when the fact is taken into consideration that if any improvement to a garment involves an added expense of but a few cents or even of one cent to the production price of cheap contract-labor-made articles of apparel such additional cost will prove an effective bar to its adoption, no matter how meritorious it might be, as the value for such apparently-trivial saving in time and labor will be appreciated. 70

To effect the saving referred to, each safety-pocket performs the double function of a pocket proper and a closure or flap for the mouth of the next succeeding pocket throughout a series of pockets. By reference to Figs. 1 and 2 this will be clearly understood. In carrying the invention into effect in this instance three pieces of material (designated, respectively, 1, 2, and 3) are cut to the desired form, the bottom of each piece being shaped to present a flap 4 integral with the 85 pocket and preferably reinforced, as by an added thickness of material held in place by lines of stitches 5, the corners of the flaps being formed to overlap the corners of the adjacent pocket, as shown at 6, whereby to prevent money in any form from working out at these points. The upper edge of the pocket may be reinforced by having the mouth portion folded upon itself to form a double thick- 90 95 100

ness of goods and held by a line or lines of stitches 7. The safety-pocket blanks being thus finished, they are laid upon the blank A, with the lower flap of each blank overlapping the mouth portion of the next adjacent pocket, and are then secured to the blank A by rows of side stitches 8 and cross-rows of stitches 9, the latter closing the blank and forming the bottom of the pocket. The sides 10 of the pockets B may be turned under to obviate the presentation of a selvage edge.

A suitable fastening device, such as an ordinary spring glove-fastener b, may be employed to secure the flaps over the pocket-mouth, or, if preferred, a button and button-hole may be employed for the same purpose. The fastening device of whatever character employed may be so attached to the parts of a safety-pocket and in such manner as to render it difficult to be operated except by the person wearing the garment. When the pockets are thus positioned and secured to the blank A, the latter may be folded, as shown in Fig. 4, and its free edges secured together 25 by a line or lines of stitches 10, presenting the pocket proper, which may in the usual manner be secured to the garment.

Where the pocket is to be used as a front pocket on trousers, the flap of the upper safety-pocket may be made of the cloth of the 30 trousers, thus giving a finished appearance to the trousers at this point, as usual.

Having thus fully described my invention, what I claim as new, and desire to secure by Letters Patent of the United States, is— 35

1. A safety-pocket comprising a pocket-blank proper, and attached supplemental blanks forming the safety-pockets, the bottom of each supplemental blank constituting the flap or mouth-closure for the next adjacent 40 pocket, substantially as described.

2. A safety-pocket comprising a pocket-blank proper, attached supplemental blanks forming the safety-pockets, the bottom of each supplemental blank constituting the flap 45 or mouth-closure for the next adjacent pocket, and fastening means carried by the supplemental pockets, substantially as described.

In testimony whereof I affix my signature in the presence of two subscribing witnesses. 50

MAX BERNSTEIN.
